(57) **CLAIM**

The ornamental design for an exercise machine, as shown and described.

DESCRIPTION

FIG. 1 illustrates a front perspective view of an exercise machine showing the new design.

FIG. 2 illustrates a front orthogonal view thereof;

FIG. 3 illustrates a front perspective view thereof;

FIG. 4 illustrates a left orthogonal view thereof;

FIG. 5 illustrates a rear orthogonal view thereof;

FIG. 6 illustrates a right orthogonal view thereof;

FIG. 7 illustrates a top elevational view thereof; and

FIG. 8 illustrates a bottom elevational view thereof.

FIG. 9 illustrates a front perspective view of an alternate position of the exercise machine;

FIG. 10 illustrates a rear perspective view thereof; and,

FIG. 11 illustrates a rear perspective view thereof.

The broken lines showing are included for the purpose of illustrating the environment of the design only and form no part of the claimed design.

1 Claim, 11 Drawing Sheets
